UNITED STATES PATENT OFFICE.

ROBERT H. MOORE AND MARGUERITE E. MOORE, OF NEW YORK, N. Y.

PASSENGER-CAR.

No. 902,431.

Specification of Letters Patent.

Patented Oct. 27, 1908.

Application filed July 15, 1908. Serial No. 443,645.

To all whom it may concern:

Be it known that we, ROBERT H. MOORE and MARGUERITE E. MOORE, citizens of the United States, and residents of No. 40 West Sixty-fifth street, in the city of New York, county of New York, and State of New York, have invented a new and useful Improvement in Passenger-Cars, of which the following is a specification.

Our invention relates to the improvement on passenger-cars, and the objects of our improvement are:

First. To facilitate a simultaneous ingress and egress of passengers.

Second. To separate passengers boarding from those leaving.

Third. To save time.

We obtain these objects by the means illustrated in the different views, in which— Figure 1 is a sectional view of the end of a passenger-car with the improvement on it. Fig. 2 is a top view of the same car after the removal of roof.

Similar letters refer to similar parts throughout the different views.

a. indicates a stanchion vertically adjusted to floor and located in the center or thereabout of a wide doorway on each side of the ends of a passenger-car, the said stanchion having a socket for temporarily engaging the free end of the pivoted bar c.

b. indicates a stanchion, vertically adjusted to floor and centrally located between the stanchions a and a on each side of the ends of a passenger-car.

c. indicates a bar, one end of which is

pivotedly mounted on stanchion b, the purpose of this bar being to create a railing on either side of the ends of a passenger-car, by transferring the free end of said bar from the socket in stanchion on one side of car, to the socket in stanchion on opposite side of car, the railing serving to separate the passengers leaving from those boarding, on either side of the ends of a passenger-car.

d. indicates a pivot in stanchion b.

e. indicates a socket in stanchion a.

f. indicates a wide doorway on each side of the ends of a passenger-car.

g. indicates a doorway.

h. indicates seats.

i. indicates windows.

We claim:

In a passenger-car, the combination of a wide doorway on each side of the ends of car, and a stanchion vertically adjusted to floor and located in the center or thereabout of each doorway, a socket in said stanchion, and a stanchion vertically adjusted to floor and centrally located between the stanchion in doorway on each side of car, and a bar one end of which is pivotally mounted to said centrally located stanchion, the free end of said bar being temporarily engaged in socket of stanchion on either side of car, for the purpose all substantially as set forth.

ROBERT H. MOORE.
MARGUERITE E. MOORE.
